SUBMERSIBLE PUMP AND ELECTRIC MOTOR
UNIT

James Fred Haldeman, Martinsville, Ind.

Original No. 2,004,866, dated June 11, 1935, Serial
No. 746,919, October 4, 1934. Application for
reissue February 18, 1937, Serial No. 126,528

7 Claims. (Cl. 103—87)

This invention relates to a pump and electric motor unit designed to efficiently operate when submerged and for instance when used in an aquarium as a fountain, in a well for irrigating purposes, or otherwise.

It is particularly aimed to provide a novel construction which will resist erosive action of the water to a minimum, having the stator air and water tight and also having the laminations of the armature plated with copper or other metal, the stator preferably being within an enclosure containing an insulating compound which serves to conduct and dissipate the heat from the motor.

It is also aimed to provide a novel pumping construction and casing in association with the electric motor.

The more specific objects and advantages will become apparent from a consideration of the description following taken in connection with accompanying drawing illustrating an operative embodiment.

In said drawing:—

Figure 1 is a substantially central vertical sectional view through the unit or assembly.

Figure 2 is a horizontal sectional view taken on the line 2—2 of Figure 1.

Figure 3 is a detail elevation of the pump casing.

Figure 4 is a plan view of said casing, and Figure 5 is a fragmentary elevation, partly broken away disclosing the construction of the motor armature.

Referring specifically to the drawing wherein like reference characters designate like or similar parts, an air and water tight, metallic base or casing is provided at 10 containing the stator 11 of the motor. This stator comprises a field core 12 and associated coils 13 which surround a central depending well 14 forming a part of the casing 10. The current supply wires for the stator are shown at 15 and lead into the casing 10 through any suitable water and air tight compression fitting as at 16. Said field core 12 is held in place by a suitable number of bolts 17 which pass therethrough, and which are secured to the upper wall of casing 10 by means of nuts 18 and 19, threaded on the bolts and engaging opposite sides of said wall. The heads 20 of the bolts are lowermost so that the core will rest thereon.

The casing 10, aside from the well 14, is filled with a suitable compound 21 so as to conduct the heat away from the core and dissipate it, such compound for instance being of coal tar or asphaltic base.

The rotor of the motor 22 comprises an armature made up of laminations 23 carried by a vertical shaft 24, the latter being made of any suitable rust-resisting metal. Said laminations or

plates 23, prior to assembly or connection to the shaft 24 are individually plated with copper, zinc or any other preferred metal to resist corrosion. After assembly of the plated plates or laminations 23 on the shaft 24, such plates as a unit are again plated with copper, zinc or other preferred metal. The plating is preferably effected by electro-deposition and is shown at 25. A suitable bearing 26 is provided in the base well 14 for the lower end of the shaft 24 and such shaft is journaled in a bearing 27, screw-threaded at 28 in the upper end of the well 14, in a water tight manner. The shaft 24 extends above the bearing 27 so as to drive the pump assembly.

An annular plate or disk 29 has the upper ends 15 of the bolts 17 passing removably therethrough and said upper ends of the bolts 17 also removably pass through a base flange 30 of a pump casing 31, nuts 32 being screwed on the upper ends of the bolts and tightened against the 20 flange 30. Said casing includes a chamber 33, in which are located piston vanes 34 attached to the upper end of the aforesaid shaft 24 so as to form the pump. It will be noted that the plate 29 extends inwardly under the pump chamber 25 33, having an enlarged central opening at 36 so that water may pass into the pump chamber from the space 37, between the top wall of casing 10 and the plate 29, due to the spacing effected by nuts 19.

The side wall of the pump chamber is perforated as at 38 so that the water may leave the same and the casing has integral therewith an upper hollow section 39, perforated at 40, so that discharging water may enter the perforations and 35 flow through a discharge pipe 41.

Said discharge pipe 41 is screw-threaded as at 42 to the upper end of the casing part 39. Between the base 43 of said pipe, and a shoulder 44 on said section 39, a bell housing 45 is removably 40 fastened, which bell telescopes over but is not connected to the peripheral edge of the plate 29. A water tight joint, however, is maintained through the contact of said peripheral edge of plate 29 with the interior wall of bell housing 45. Such bell housing 45 extends below the plate 29, flaring outwardly at its lower edge, so as not to close the passageway 37.

It is to be noted that the electric motor parts shown are substantially the same as are used in 50 electric motors of the conventional shaded pole alternating current induction motor, being modified, however, as previously described to accommodate use in the present construction, particularly as regards the mounting of the core 11, the 55 plating of the rotor, the mounting of the rotor and the accommodation of the compound 21.

In the use of the device, the impeller or piston afforded by the blades 34, will draw fluid, when the unit or assembly is submerged, through pas- 60

sageway 31, opening 36, ports 28, between the casting of the pump and hood or bell housing 45, through ports 40 and thence through the discharge pipe 41.

5 Various changes may be resorted to provided they fall within the spirit and scope of the invention.

I claim as my invention:

1. A device of the class described comprising a 10 casing having a chamber, an impeller in said chamber, a discharge pipe leading from the casing, said discharge pipe having an inlet, said chamber having an outlet opening, a hood secured over said casing by said discharge pipe to 15 confine the discharge from the chamber and cause it to pass into the inlet of the discharge pipe, a plate adjacent the bottom of the hood surrounded by the hood and having an opening constituting an inlet for the chamber, a base 20 having an electric motor therein, the armature shaft of the motor extending above the base and through said plate opening and driving the impeller, bolts connecting the field core of the motor, said casing and plate together, and means 25 spacing the plate and casing from the base and surrounding said bolts.

2. A device of the class described comprising a 30 casing having a chamber, an impeller in said chamber, a discharge pipe leading from the casing, said discharge pipe having an inlet, said chamber having an outlet opening, a hood secured over said casing by said discharge pipe to 35 confine the discharge from the chamber and cause it to pass into the inlet of the discharge pipe, a plate adjacent the bottom of the hood surrounded by the hood and having an opening constituting an inlet for the chamber, a base 40 having an electric motor therein, the armature shaft of the motor extending above the base and through said plate opening and driving the impeller, bolts connecting the field core of the motor, said casing and plate together, and means 45 spacing the plate and casing from the base and surrounding said bolts, said base having a central well in which the rotor is disposed, and a removable bearing for the rotor shaft screw-threaded in the upper end of the well.

3. A device of the class described comprising a 50 casing having a chamber, an impeller in said chamber, a discharge pipe leading from the casing, said discharge pipe having an inlet, said chamber having an outlet opening, a hood secured over said casing by said discharge pipe to 55 confine the discharge from the chamber and cause it to pass into the inlet of the discharge pipe, a plate adjacent the bottom of the hood surrounded by the hood and having an opening having an inlet for the chamber, a base 60 having an electric motor therein, means spacing said plate and base, the armature shaft of the motor extending above the base and through said plate opening and driving the impeller, and means connecting the field core of the motor, said casing and plate together.

4. In a device of the class described, the combination with a supporting base unit including a 65 motor enclosed therein with an upwardly extending shaft having one end exposed above the base of an apertured superposed plate rigid with the unit but in spaced relation thereto, a superposed flanged pump chamber forming member rigid with the plate and including a side opening discharge, a pump impeller in the pump chamber secured to the shaft end therein, a housing peripherally enveloping the pump chamber, in-

teriorly engaging the peripheral edge of the plate and forming an outer chamber therewith, tubular extension means carried by the member having a lateral intake to the outer chamber and a longitudinal discharge, said tubular extension 5 means supporting said housing, and tubular means coaxial with the longitudinal discharge securing the extension means and housing together.

5. In a device of the class described, the combination with a supporting base unit including a 10 motor enclosed therein with an upwardly extending shaft having one end exposed above the base of an apertured superposed plate rigid with the unit but in spaced relation thereto, a superposed flanged pump chamber forming member rigid with the plate and including a side opening discharge, a pump impeller in the pump chamber secured to the shaft end therein, a housing peripherally enveloping the pump chamber, in- 15 teriorly engaging the peripheral edge of the plate and forming an outer chamber therewith, tubular extension means carried by the member having a lateral intake to the outer chamber and a longitudinal discharge, said tubular extension 20 means supporting said housing, and tubular means coaxial with the longitudinal discharge securing the extension means and housing together, the tubular extension means having a shoulder adjacent that end remote from the 25 pump chamber for supporting said housing, said shouldered end being threaded and the tubular means having threaded connection therewith.

6. In a device of the class described, a supporting base unit including a motor enclosed 30 therein with an upwardly extending shaft, a housing supported in spaced relation to said unit, a tubular discharge extending upwardly from the housing and centrally thereof and coaxial with the motor shaft axis, a pump chamber 35 within the housing and including a lateral discharge into the housing, the pump chamber having a central intake immediately above the base unit and through which the upwardly extending shaft extends, a pump member in said chamber 40 and mounted upon said shaft therein, another chamber within the housing and having a lateral intake into the housing for receiving therefrom liquid discharged into the housing from the pump chamber, said another chamber longitudinally 45 discharging to the tubular discharge, one wall of the pump chamber extending laterally beyond the same and having engagement with the housing for closing the housing chamber, said pump chamber having nested relation within said hous- 50 ing.

7. A device of the class described comprising a 55 casing having a chamber, an impeller in said chamber, a discharge pipe leading from the casing, said discharge pipe having an inlet, said chamber having an outlet opening, a hood to 60 confine the discharge from the chamber and cause it to pass into the inlet of the discharge pipe, a plate adjacent the bottom of the hood surrounded by the hood and having an opening 65 constituting an inlet for the chamber, a base having an electric motor therein, the armature shaft of the motor extending above the base and through said plate opening and driving the impeller, bolts connecting the field core of the motor, said casing and plate together, and means 70 spacing the plate and casing from the base and surrounding said bolts.
